UNITED STATES PATENT OFFICE.

WILLIAM McCONWAY, JR., OF PITTSBURGH, PENNSYLVANIA, ASSIGNOR TO McCONWAY & TORLEY COMPANY, OF PITTSBURGH, PENNSYLVANIA, A CORPORATION OF PENNSYLVANIA.

DRAFT APPLIANCE FOR RAILWAY-VEHICLES.

1,148,029.

Specification of Letters Patent. Patented July 27, 1915.

Application filed July 8, 1914. Serial No. 849,691.

To all whom it may concern:

Be it known that I, WILLIAM McCONWAY, Jr., a citizen of the United States, residing at Pittsburgh, in the county of Allegheny and State of Pennsylvania, have invented certain new and useful Improvements in Draft Appliances for Railway-Vehicles; and I do hereby declare the following to be a full, clear, and exact description of the invention, such as will enable others skilled in the art to which it appertains to make and use the same.

My invention relates to the construction of car couplers and more especially to those of the type, commonly applied to locomotives and locomotive tenders, in which the coupler shank is comparatively short and is pivotally connected to a coupler pocket or bracket member.

It is the object of my present invention to produce a railway draft appliance of the class indicated in which drooping of the coupler head due to the wear of tires, permanent set of springs or the like may be readily compensated for by simple and easily manipulated means forming a part of the draft appliance itself.

To this end my invention, generally stated, involves the combination of a bracket member having a pocket for the reception of the shank of a coupler and also having laterally disposed recesses which communicate with said pocket, a pivoted coupler whose shank extends into the pocket, and a yoke engaging the lower side of the coupler in advance of the bracket member to thus support the coupler, said yoke being adapted to enter the laterally disposed recesses of the bracket member and being also capable of assembly in a plurality of positions with respect to the bracket member, to thereby vertically adjust the height of the coupler.

In the drawings illustrating my invention, the scope whereof is defined by the appended claims, Figure 1 is a plan view of a tender coupler embodying my invention; Fig. 2 is a view showing the bracket member in horizontal section and the adjusting yoke and coupler in plan; Fig. 3 is a view in which the bracket member, adjusting yoke and the shank of the coupler are shown in vertical section, while the coupler head and the pivot pin are shown in elevation; Fig. 4 is a view, partly in front elevation and partly in vertical section, showing the rela-

tive positions of the parts of the device when the coupler is in its lowest position, the bracket member and adjusting yoke being shown in elevation and the shank of the coupler being in section; and Fig. 5 is a detail perspective view of the adjusting yoke.

In the drawings, 1 indicates a bracket member or coupler pocket which is adapted to be secured to an appropriate part of the locomotive, tender or other railway vehicle to which it is to be applied. The bracket member 1 is fashioned with an outwardly flaring pocket 2 which is adapted to receive and permit a lateral swinging movement of the shank of the coupler, the vertical height ⁶⁰ of the pocket being somewhat greater ^t than the height of the coupler shank in order to permit the latter to be adjusted vertically within the pocket. Near the mouth of the pocket 2 are laterally disposed recesses ⁶⁵ 3 which, as shown, are preferably arranged in pairs, the recesses of each pair being separated from each other by a horizontally extending seat 4.

The coupler 5, which is connected to the bracket member 1 by means of a pivot pin 6, is preferably provided with a bifurcated or slotted shank the upper branch 7 whereof may be advantageously formed at its rear end with a segmental lug or projection 8. ⁷⁰ This projection 8 is adapted to enter and be movable in either of the corresponding arcuate channels 9 at the base of the pocket 2 of the bracket member 1, such a construction serving to prevent upward movement of ⁷⁵ the rear end of the coupler shank when the coupler is in service and thus assisting in preventing drooping of the coupler head.

The vertical adjustment of the coupler with relation to the bracket member 1 is effected by means of a yoke 10 which is preferably so formed as to also furnish a support for the coupler 5 beyond the forward end of the bracket member. This yoke 10, if desired, may be of bowed or angular form, ⁸⁰ is fashioned with a laterally extending horizontal shelf 11 that is adapted to engage the underside of the coupler 5 in advance of the lower wall of the pocket portion of the bracket member 1, to thus furnish a support for the coupler at a considerable distance in advance of the pivot pin 6. Adjacent to the ends of the supporting shelf ⁸⁵ 11 are corresponding vertically extending members or bars 12 which serve as a means ⁹⁰ 105 110

of uniting the shelf 11 with a corresponding parallel shelf 13. The end portions of the shelf 13 are adapted to enter the corresponding laterally disposed recesses 3 of the bracket member 1, while the central portion of the shelf 13 extends through the slot in the shank of the coupler. The lower member or branch of the bifurcated coupler shank passes between the shelves 11 and 12 of the adjusting yoke and is adapted to swing or oscillate laterally between the vertically extending lateral members 12.

In assembling the device the yoke 10 may be threaded on the shank of the coupler, 15 the upper bar or shelf 13 of said yoke being inserted in the slot between the upper and lower arms of the shank. The yoke 10 and the coupler shank may be then simultaneously inserted into the pocket 2 of the 20 bracket member 1 and be secured in position by means of the pivot pin 6. When the ends of the upper shelf 13 of the yoke 10 are in the lower pair of laterally disposed recesses 3 the coupler 5 is in its lowest position. By 25 assembling the parts so that the ends of the shelf 13 enter the upper pair of recesses 3 and bear upon the tops of the seats 4, the coupler 5 may be maintained in a higher position of adjustment with respect to the 30 bracket member 1.

I claim:

1. In a draft appliance for railway vehicles, the combination with a bracket member having a pocket therein, of a coupler having a shank which is adapted to extend into said pocket, means for connecting said coupler shank to said bracket member, and means separate from said connecting means for adjusting the vertical height of said coupler with respect to said bracket member, said adjusting means involving a device provided with a shelf which is adapted to supportingly engage the lower side of said coupler beyond said bracket member and said adjusting means also including means for limiting upward vertical movement of said coupler with respect to said bracket member.

2. In a draft appliance for railway vehicles, the combination with a bracket member having a pocket for the reception of the shank of a coupler and also having laterally disposed recesses communicating with said pocket, of a coupler having a shank extending into said pocket, a device for pivotally connecting said coupler shank and bracket member, and means engaging the lower side of said coupler beyond said bracket member for supporting said coupler, said means also entering the said laterally disposed recesses of said bracket member and being separate from said connecting device and being capable of assembly in a plurality of positions with respect to said bracket mem- 66 ber.

3. In a draft appliance for railway vehicles, the combination with a bracket member having a pocket for the reception of a coupler shank, of a coupler having a shank extending into said pocket and capable of a 70 swinging movement therein, and means engaging the lower side of said coupler beyond said bracket for supporting said coupler, said means involving a device which is provided with a shelf extending beneath 75 said coupler and which is adapted to engage said bracket member above the floor of the coupler shank receiving pocket therein, and a portion of the shank of said coupler projecting rearwardly through said supporting 80 means.

4. In a draft appliance for railway vehicles, the combination with a bracket member having a pocket for the reception of a coupler shank, of a coupler having a slotted 85 shank extending into said pocket, a pivot pin for connecting said bracket member and coupler shank, means located rearwardly of said pivot pin and above the slot in said coupler shank for preventing upward movement of said shank with respect to said bracket member, and means extending into the slot of said coupler shank and located forwardly of said pivot pin and having a portion below the slot in said coupler shank 90 for preventing downward movement of said coupler with respect to said bracket member.

5. In a draft appliance for railway vehicles, the combination with a bracket member having a pocket therein, of a coupler having a shank which extends into said pocket, means for connecting said bracket member and coupler shank, and a device for supporting said coupler in a plurality 100 of positions of vertical adjustment, said device involving a member which is formed with a plurality of shelves which lie in parallel planes, one of said shelves extending forwardly beyond the other.

6. In a draft appliance for railway vehicles, the combination with a bracket member, of a coupler having a slotted shank, means for connecting said coupler to said bracket member, and means for supporting 115 said coupler in a plurality of positions of vertical adjustment with respect to said bracket member, said supporting means involving a yoke having a portion which extends into the slot of said coupler shank and also having a portion which extends under said coupler shank.

7. In a draft appliance for railway vehicles, the combination with a bracket member having a pocket for the reception of the shank of a coupler, of a coupler having a shank extending into said pocket, means for pivotally connecting said coupler shank and bracket member, and a yoke having a shelf which supportingly engages the lower 125 130 135 140 145 150 155 160 165 170 175 180 185 190 195 200 205 side of said coupler shank beyond said bracket member, said yoke being also provided with vertically extending laterally disposed members and being capable of assembly in a plurality of positions with respect to said bracket member to thereby vertically adjust the height of said coupler.

8. In a draft appliance for railway vehicles, the combination with a bracket member, of a coupler, means for pivotally connecting said bracket member and coupler, and a yoke for supporting said coupler in a plurality of positions of vertical adjustment with respect to said bracket member, said yoke having a plurality of connected laterally extending shelves which are in different planes and one of which extends in advance of another.

9. In a draft appliance for railway vehicles, the combination with a bracket member having a pocket for the reception of the shank of a coupler and also having laterally disposed recesses communicating with

said pocket, of a coupler having a slotted shank which extends into said pocket, a 25 pivot pin connecting said coupler and bracket member, and a yoke which is adapted to extend into said laterally disposed recesses and to engage said coupler, said yoke having a plurality of parallel shelves one of 30 which extends forwardly beyond the said bracket member and one of which extends through the slot of said coupler shank.

10. A coupler supporting member for couplers of the engine and tender type, said 35 member involving connected parallel shelves which are in spaced relation and one of which extends in advance of another.

In testimony whereof I affix my signature, in the presence of two subscribing witnesses.
